(57) **CLAIM**

The ornamental design for a lantern box, as shown and described.

DESCRIPTION

FIG. 1 is a front, top, left-side perspective view of the lantern box;

FIG. 2 is a front elevational view thereof;

FIG. 3 is a top plan view thereof;

FIG. 4 is a right-side elevational view thereof;

FIG. 5 is a left-side elevational view thereof;

FIG. 6 is a rear elevational view thereof; and,

FIG. 7 is a bottom plan view thereof.

The cross-hatching depicts areas of the lantern box having a surface composed of textured fabric.
